UNITED STATES PATENT OFFICE.

WILLIAM B. D. PENNIMAN, OF BALTIMORE, MARYLAND.

APPARATUS FOR CRACKING OILS.

Application filed May 5, 1917. Serial No. 166,587.

To all whom it may concern:

Be it known that I, WILLIAM B. D. PENNIMAN, a citizen of the United States of America, residing in the city of Baltimore, State of Maryland, have invented certain new and useful Improvements in Apparatus for Cracking Oils, of which the following is a specification.

The present invention relates to the distillation and cracking of the heavier petroleum oils in the production of gasoline, using steam or other fluid as a heat transfer medium and preferably heating the oils from within in accordance with my Patent No. 766,841, which describes means for obtaining high steam temperatures at low pressures, as compared to the pressures of wet or saturated steam at corresponding temperatures. By cracking I mean the operation by which the hydrocarbons of high molecular weight and boiling point are broken down by heat into two products one of which is more volatile than the material cracked. In this operation some of the important difficulties encountered which are thought to be overcome or largely overcome by the present device, are the deposit of coke in the still, which reduces the efficiency of heating surfaces and is accompanied by the formation of an excess of permanent gas, and the production of an excess of permanent gas by overheating, independently of the formation of coke; also the danger of explosion or fire or structural damage to the still incident to direct heating.

The margin between the temperature necessary to the production of the highest percentage of gasoline from these heavier oils and the temperature at which excessive amounts of coke and gas are formed is rather slight and accurate regulation of the heating effect or temperature of the heat transferring fluid or transfer medium is necessary. The difficulty and danger involved in working with the pressures incident to saturated steam at the temperatures necessary to the cracking of heavy oils will be appreciated. According to the disclosure

of my patent above referred to, this difficulty is overcome by mixing superheated and wet steam or steam and water, or some less easily vaporized fluid from two sources at different temperatures. In the present instance, the heat transfer medium or vehicle is preferably steam supplied from any suitable boiler and brought in heat exchanging relation with the oil by passing through coils or any suitable container in contact with the oil. The regulation of the temperature of the coils and their heating effect is accomplished by supplying to wet steam on its way to the coils the necessary degree of heat giving the desired temperature without increasing the pressure, the heating effect of the superheater being adjusted preferably by automatic means to regulate the temperature to which the steam is superheated or to give the desired heating effect at the point of application. In this way a high temperature is attained without involving a pressure in excess of that corresponding to the temperature at which the wet or saturated steam is supplied; and regulation of the temperature is accomplished in an easy and convenient manner.

In the accompanying drawing I have illustrated an apparatus embodying my invention.

Figure 1 is an elevation showing the boiler, superheater and certain thermostatic apparatus for controlling the superheater; and

Figure 2 is an elevation of the still and condenser, the two figures being so arranged that joined end to end they form a single view of the entire apparatus.

Referring to the drawings by numerals, the apparatus consists of a suitable still 1 containing oil and the still may have a stillhead or vapor chamber 2 opening into the space above the oil and connected to a condenser 4. Looking at the other end of the apparatus, there is a steam boiler and furnace 5 and a steam outlet or delivery pipe 6 connected to a superheater 7. This superheater contains a coil of pipe 8 and a

furnace or burner 9 supplied with fuel from any suitable source. While any type of heater or furnace may be used, I have shown a gas or oil burner as most easily controlled.

5 If an ordinary furnace burning coal or pulverized fuel is used, it may be controlled according to well-known principles through the thermostatic apparatus described and shown herein. The furnace as shown is connected to the fuel supply by a pipe 10 controlled by a valve 11 which is preferably automatic and operated by thermostatic apparatus 12 which is preferably of the general type described in my Patent No. 902,600.

10 The valve gear 12 is electrically driven and includes a motor 13 having sets of reversing connections 14, 15 connected to a U-shaped tube 16 containing the terminals of the three wires 17, 18 and 19 and sufficient mercury to fill the lower portion of the bend. The U-tube is connected by a pipe 20 to an air bulb 21 in the pipe 22 adjacent to the heating elements in the still, the pipe 22 being the steam pipe from the superheater to the still. These heating elements are shown as including a series of upper headers 23 and a series of lower headers 24 connected by suitable pipes 25 and separated by baffles 26 and 27. Steam enters by the pipe 22 and passes through the system from left to right in Figure 2, the waste steam being used in any convenient manner, and the oil is passed through the still preferably in the opposite direction.

15 In the form of the invention shown, oil is supplied to the still by way of a pipe 28 and a pump 29 and after passing in contact with the heating system and being heated to and maintained for a sufficient period at a predetermined temperature sufficient to crack and form volatile products from the available crackable heavy oils, it is drawn off at the outlet 30. In the form of the apparatus shown, the pump 29 is driven by an electric motor 31 controlled by a contact float 32 in the circuit which serves to make the circuit whenever the oil is below a predetermined level and hold it closed until it is pumped up to that desired level when the current is broken and pumping ceases.

20 However, in the normal operation of the device, the float occupies a position in which the pump runs at a sufficient speed to compensate for the discharge and evaporation.

25 The entire system is maintained under pressure as hereinafter described and the heating by means of the heating elements 23, 24 and 25 serves to crack and vaporize the available portions of the heavy oils, producing gasoline and a small amount of permanent gas; also some of the oil is usually vaporized without being cracked. This may be further treated to advantage in the still-head and to this end, I may when it is deemed desirable provide heating means in the stillhead for further heating the vapor. This is done in stillhead chamber 33. Such heating means is shown in the form of a coil 35 supplied with steam from the boiler 5 superheated to the desired degree in a super-heater 36; the temperature being controlled in substantially the same manner as the temperature of the coil 23, 24, etc. by means of an automatic valve 37 operated by valve gear 38 of substantially the same type as the valve gear 12 shown in connection with the valve 11, the same being controlled by thermostatic means consisting of a U-shaped tube 39, and an air bulb 40 in the pipe 42 leading from the superheater 36 to the coil 35 or it may be placed in any position in which it will be affected proportionately to the heating effect on the vapor of the coil 35. I may also provide a coil 41 used as a cooling means to separate the uncracked oils 8 from the gasoline by condensation, the coil, if used being placed in a second vapor chamber 34. The coil 41 is just sufficiently below the temperature of the vapors to condense the heavy oils without condensing the gasoline. For this purpose I use wet steam led from the boiler by the pipe 60. The passage of steam through this pipe is controlled by an automatic valve 61 and valve gear 62 which may be of the type described in my Patent No. 933,577 consisting of a motor 64 and a U-tube 65 connected to an air bulb 66 in the passage 67 leading from the condenser chamber 34. The U-tube contains three contact points 68 by which the motor 11 is controlled as to stopping, starting and reversing according to the position of the mercury which is controlled by the air bulb according to the temperature at that point. In this way, just sufficient wet steam to give the desired amount of cooling is applied to the cooling coil 41. The pipes 69, 70 conducting steam from both coils may be led to pipe 22 between the superheater and the air bulb or the steam from the coils 11 may be otherwise disposed of.

30 The vapor is passed by way of a suitable pipe 48 to the condenser 4 where the gasoline is condensed and collected in a suitable reservoir 49, the permanent gases passing by way of a pipe 50 to the furnace or to a gasometer, the outlet being controlled by an automatic valve 51 operated by a motor 52, the connections being made through a pressure indicator 53, the pivot of the indicator 12 hand 54 being connected to a ground wire and the forward and reverse wires being connected to two terminals 55 and 56 at the limits of the needle's swing, i. e., determining the variations of pressure permitted in the 12 system so that when the pressure increases sufficiently to cause the needle to contact the terminal 56, the motor runs forward and the valve is opened, and when it drops sufficiently to cause the needle to contact the 13

terminal 55, the motor is operated in the opposite direction, partially closing the valve.

While I have described specifically the details of a complete apparatus involving numerous features, this is done in order that the nature and operation of such a complete apparatus capable of use for the purposes of my invention may be clearly understood. However, the scope of the protection sought is much broader than the details of the apparatus. The wet steam may be taken from any suitable source; any kind of a superheater which is available or found convenient may be used and any kind of heater, whether burning liquid, gaseous, solid or pulverized fuel; it is not essential that all the steam be passed through the superheater; the valves may be automatically controlled or otherwise and it is not essential that the superheater regulating valve control the fuel supply, it may operate through some other agency; the apparatus for treating the vapors in the stillhead may be varied, either the heating or cooling element or both may be omitted; the oil may be passed through the still in any desired manner; and any means for maintaining the pressure in the still may be used.

What I claim and desire to secure by Letters Patent is:

1. In an apparatus for cracking oils under pressure, a still for the oil, a container for steam in contact with the oil, means for supplying steam, a superheater for raising the temperature of the steam as it approaches the still without increasing the pressure, means for regulating the temperature of the superheater, and a thermostat controlled by the temperature of the steam supplied to the still and controlling the action of such regulating means.

2. In an apparatus for cracking oils, in combination a still for the oil, means for heating the oil in the still, consisting of a container for steam in contact with the oil, means for supplying wet steam, means for superheating the steam, means for adjusting the temperature of the superheater, a thermostat in the steam passage near the point where it enters the said container in contact with the oil, and connections from the thermostat to the adjusting means whereby the thermostat controls the adjusting means.

3. In an apparatus for cracking oils under pressure, a still for the oil, a container for steam submerged in the oil, a boiler for supplying wet steam, a superheater between the boiler and the still, means for supplying fuel in the form of a fluid to the superheater, a valve controlling the supply of fuel, a thermostat the condition of which corresponds to the thermal conditions to be maintained in the still, and

connections between the thermostat and the valve in the fuel pipe whereby the temperature of the superheater is made to correspond to and is controlled by the temperature of the steam container in the still.

7c

4. In an apparatus for cracking oils under pressure, a still, a vapor chamber or stillhead, means for heating the oil including a container for steam submerged in the oil, a boiler for supplying wet steam, a pipe connecting the boiler to the container in the still, a superheater in the pipe line, a fluid burner for heating the superheater, a valve controlling the supply of fluid, a thermostat in the steam pipe near where it enters the still, and connections from the thermostat to the valve in the fuel supply whereby the temperature of the steam entering the still is raised to and maintained at a predetermined normal.

85

5. In an apparatus for cracking oils under pressure, a still for containing oil, means for heating the still, a vapor chamber communicating with the still space above the oil, a steam container in the chamber, a boiler for supplying wet steam, a pipe connecting the boiler to the steam container, a superheater between the boiler and the steam container, means for controlling the temperature of the superheater, a thermostat exposed to a temperature proportionate to that of the container in the vapor chamber, and connections from the thermostat to the controlling means for the superheater whereby the temperature of the superheater 100 is controlled according to the temperature of the container.

95

6. In an apparatus for cracking oils, a still for containing the oil, steam containers in contact with the oil, a source of wet steam, a pipe leading from the said source to the said containers in the still, a superheater in the pipe line, thermostatic means controlled by the temperature of the steam in the container for regulating the temperature of the superheater, a vapor chamber in communication with the still space over the oil, a steam container therein, means for supplying wet steam to the steam container, and thermostatically controlled means under the influence of the thermal condition of the vapor which is passed in contact with the steam container, the said thermostatic means controlling the supply of wet steam.

110

7. In an apparatus for cracking oils, a still for containing the oil, steam containers in contact with the oil, a source of wet steam, a superheater to raise the temperature of the steam, thermostatic means controlled by the temperature of the steam in the container for regulating the temperature of the superheater, a vapor chamber in communication with the still space over the oil, means for heating the vapors after they pass from the oil in the form of steam containers, means

115

120

125

130

for superheating the steam entering said containers, thermostatic means controlled by the temperature of the steam entering said containers controlling the temperature of the last-mentioned superheater, a steam container beyond the vapor heating device, means for supplying wet steam to the steam container to condense a portion of the vapor, and thermostatically controlled means under 10 the influence of the thermal condition of the

vapor which is passed in contact with the steam container, the said thermostatic means controlling the supply of wet steam.

Signed by me at Baltimore, Maryland, this 3rd day of May 1917.
